UNITED STATES PATENT OFFICE.

CURTIS M. WILLOCK, OF DEFIANCE, OHIO, ASSIGNOR TO THE AMERICAN STEEL
PACKAGE COMPANY, OF DEFIANCE, OHIO, A CORPORATION OF OHIO.

PACKING-CASE.

1,146,116.

Specification of Letters Patent. Patented July 13, 1915.

Application filed July 27, 1909. Serial No. 509,784.

To all whom it may concern:

Be it known that I, CURTIS M. WILLOCK, a citizen of the United States, residing at Defiance, in the county of Defiance and 5 State of Ohio, have invented certain new and useful Improvements in Packing-Cases, of which the following is a specification.

My invention relates to improvements in metal packing cases especially designed for 10 the transportation and storage of liquids contained in bottles and similar vessels.

The invention relates more particularly to improvements in hinged lids or covers provided with a marginal or peripheral 15 beading adapted to shut down inside and in the same plane with the beading formed by the upper edges of the case side walls, whereby a second strengthening beading is formed within adjacent to and supporting 20 said last mentioned beading substantially as shown in Kruse Patent No. 870,728, of November 12, 1907.

The hinged cover is locked or latched in its closed position by means of a spring 25 latch-bar normally engaging the free end of the cover midway between the outer corner portions thereof substantially as shown in Kruse Patents Nos. 786,299, and 892,062, of April 4, 1905, and June 30, 1908, respectively, the primary object of the invention 30 being to reinforce the free end or side of the hinged cover so as to prevent the outer corners of the cover from being forced or pried upwardly out of true horizontal alignment with the central portion of the closed lid or cover by unscrupulous parties in the 35 act of gaining access to the case contents while in transportation or storage.

With the above mentioned ends in view, 40 the invention consists in the novel construction, arrangement, and combination of parts, hereinafter described, illustrated in one of its embodiments in the accompanying drawings, and particularly pointed out in the appended claims.

Referring to the drawings, forming a part 45 of this specification, Figure 1, is a perspective view of the upper portion of a case body provided with a hinged lid or cover constructed in accordance with my invention. Fig. 2, a sectional view of the same. Fig. 3, 50 a sectional view of the lid or cover. Fig. 4, a cross sectional view of a modified form of cover truss members. Fig. 5, a similar 55 view of another modified form of same.

Similar numerals of reference designate like parts throughout all the figures of the drawings.

The case body may be of any suitable and convenient form and has its side walls 1, 60 preferably, provided at its upper marginal edges with an inwardly extending lid supporting flange 2, and curled about a wire 3, forming a peripheral beading 4.

The lid or cover 5, has its marginal edges 65 bent or curled about a wire 6, forming a peripheral beading 7. The lid or cover 5, is secured at its rear by means of hinge straps 8, which take over the wire 3, secured within the beading 4, formed about the upper 70 marginal edges of the case body.

The marginal edges of the cover are adapted to rest upon the lid supporting flange 2, and the peripheral beading 7, is adapted to shut down inside and in the 75 same plane with the peripheral beading 4, whereby a second strengthening beading is formed within adjacent to and supporting said beading.

The free end of the cover is adapted to be 80 latched and locked in its closed position by means of a spring latch-bar 9, in the present instance, taking over the wire 3, midway between the outer corner portions 5^a, thereof as shown.

As a means for preventing the prying up of the corner portions 5^a, of the cover when the same is closed the free end or side of the hinged cover is strengthened and reinforced by means of truss members, said truss 90 members, in the present instance, registering with each other and comprising a strut-bar or member 10, and a tie-bar or member 11, said members 10 and 11, in the present instance, extending transversely over and between the corner portions 5^a, and secured to each other and to the free end or side of the cover by means of rivets 12.

It will be observed that the strut bar or member 10, is interposed between and abuts 100 against the peripheral beading 7, at the sides of the cover and it should be understood that one or the other of the trussing members may be dispensed with if sufficient strength and rigidity is thereby secured.

The trussing bars or members may be of 105 any suitable and convenient channeled form, such for example,—as shown in Figs. 4, and 5, of the drawings. By virtue of the trussing members arranged and transversely dis-

105

110

posed upon the free side or end of the hinged cover, it is obvious that this portion of the cover is greatly strengthened and reinforced throughout and the corner portions 5, thereof will be held in true horizontal alinement for the purposes desired.

From the foregoing description, taken in connection with the accompanying drawings, the operation and advantages of my 10 invention will be readily understood.

Having thus described my invention, what I claim and desire to secure by Letters Patent is,—

1. In a packing case, a hinged and beaded 15 cover having its free side reinforced by a pair of transversely disposed registering truss bars arranged above and below said cover, one of said truss members abutting against the beading of said cover at the 20 outer corners thereof.

2. In a packing case, a peripherally beaded hinged cover, and a pair of transversely disposed registering truss members at the free side of said cover, one of said truss 25 members abutting against said beading at the outer corners of said cover whereby to reinforce and to hold the same in true horizontal alinement.

3. In a packing case, a case body, a hinged 30 cover therefor, means for engaging the free edge of said cover midway between the outer corners thereof when closed, and a transverse truss member riveted above the free side of said cover and extending be-

tween said corners whereby the latter are 35 reinforced in the same plane with the intermediate portions thereof.

4. In a packing case, a case body, a hinged peripherally wired cover having the free side thereof transversely trussed by means 40 of channeled strut and tie bars riveted to each other through said cover, means for supporting said cover in its closed position within and flush with the upper marginal edges of said case body, and a latch member 45 engaging said peripheral wire at the free edge of said cover when closed.

5. In a packing case, a case body having its upper marginal edges crimped into a lid supporting flange and curled about a wire 50 forming a peripheral beading, a peripherally beaded hinged cover mounted on said lid supporting flange within said first mentioned beading and flush with the same, a latch member normally engaging the free 55 side of said cover midway between the outer corner portions thereof, and a transversely extending strut bar secured above the free side of said cover and extending over and between said corner portions and abutting 60 against said cover beading.

In testimony whereof I have affixed my signature, in presence of two witnesses.

CURTIS M. WILLOCK.
